UNITED STATES PATENT OFFICE.

EDWARD A. DEWALD, OF MASSILLON, OHIO, ASSIGNOR TO THE GRISCOM-RUSSELL COMPANY, OF NEW YORK, N. Y., A CORPORATION OF DELAWARE.

APPARATUS FOR FORMING EXPANSION JOINTS.

Application filed January 26, 1922. Serial No. 531,837.

To all whom it may concern:

Be it known that I, EDWARD A. DEWALD, a citizen of the United States, residing at Massillon, in the county of Stark, State of Ohio, have invented certain new and useful Improvements in Apparatus for Forming Expansion Joints; and I do hereby declare the following to be a full, clear, and exact description of the invention, such as will 5 enable others skilled in the art to which it appertains to make and use the same.

The present invention relates to apparatus for forming expansion joints of that type consisting of a substantially cylindrical body 15 part and having a circumferential ridge or groove at a portion of its length, and is intended particularly for shaping an initial sheet of material into a cylindrical form in accordance with the improved method disclosed in my co-pending application, Serial 20 No. 531,836.

It has been proposed to form expansion joints of this type by rolling up a sheet of metal into cylindrical form and subsequently 25 pressing into the cylinder thus formed a circumferential groove or ridge at about the center of its length. Expansion joints made in this fashion are, however, open to the objection that it is inconvenient to work within 30 a joint of small diameter, and joints made in apparently identical fashion often show considerable variation. Furthermore, the depth of the groove which may be rolled into the cylinder in this fashion is limited 35 by the conformation of the material of the cylinder and the difficulty of distorting the material and the resulting expansion which may be accommodated by a single joint is correspondingly restricted.

40 It is an object of the invention to provide an apparatus for shaping material of any thickness into a cylinder having uniform curvature throughout, the apparatus being capable of producing successive cylinders 45 identical in all respects.

It is also an object of the invention to provide an apparatus by means of which joints of various diameters may be produced by a simple adjustment of the apparatus, no special parts being required.

50 It is a still further object to provide an apparatus of the above type which is power-operated and in which extensive adjustments

may be made by means of power-operated mechanism, means being provided for manually effecting minute adjustments. 55

I have illustrated a preferred embodiment of my invention in the accompanying drawings, in which—

Figure 1 is a perspective view showing a 60 corrugated sheet of material previous to being formed into a cylinder;

Figs. 2 and 3 are a sectional and plan view, respectively, illustrating the cylinder formed by my improved apparatus; 65

Fig. 4 is a plan view of my improved apparatus;

Fig. 5 is an elevational view;

Fig. 6 is an end view looking from the 70 right of Fig. 5;

Fig. 7 is a partial sectional view taken on line 7—7 of Fig. 4;

Fig. 8 is a transverse sectional view illustrating the operating rolls arranged for forming a joint of relatively small diameter; 75

Fig. 9 is a similar view showing the rolls in position to form a joint of relatively large diameter.

Referring to the drawings, Fig. 1 illustrates a sheet A of metal having a corrugation B pressed into it by means of a die. This sheet of metal is formed into a substantially cylindrical form as indicated in Figs. 2 and 3, the corrugation preferably being positioned centrally of the sheet A so that it will constitute a circumferential ridge at about the center of the length of the finished joint. The ends 4 of the sheet are welded together to form an integral joint having an unobstructed fluid passage extending through it from end to end and containing no abutting faces or edges through which leakage might occur. In operation the joint is placed between the ends of the members 95 which are to be joined, the connection being preferably accomplished by bending over the ends of the joint onto cast flanges provided with bolt holes for attachment to the members. As the ends of the members move together or draw apart under the influence of temperature changes, the corrugation B of the joint will accommodate such movement by permitting the joint to contract or elongate correspondingly.

The apparatus of the present application

is designed particularly to carry out the process of forming the corrugated sheet A into a cylindrical form. Referring to the drawings, 1 indicates the bed plate or base 5 which serves as a mounting for the operating mechanism of the apparatus, and 2 indicates the supporting base for the driving mechanism. The base members 1 and 2 may be cast integrally or each may be formed 10 as a separate unit and provided with cooperating surfaces for the purpose of fitting them together. A pair of vertical brackets or pedestals 3 is provided at each end of the base 1, each pedestal having formed on 15 its inner face a flange 5 constituting a guide track for the supporting member 6. As best shown in Fig. 7, the upper surface of a member 6 is level and serves to carry a second supporting member 7 secured to the member 6 by means of bolts 8 which extend entirely 20 through the member 6 and screw into threaded taps provided in the lower face of the member 7.

The actual operation of rolling the corrugated sheet A into a cylindrical form is 25 performed by means of cooperating rolls 9, 10 and 11 mounted for adjustment to accommodate sheets of various thickness and to produce cylinders of various diameters. 30 The roll 9 is mounted directly in the supporting member 7, upwardly extending portions 12 being provided integrally with the member 7 for the purpose of affording a bearing for the roller shaft. The roll 11 35 may also be carried directly by the member 7, but is preferably mounted for rotation in a separate block 13, which block is secured to the flat upper surface of the member 7 by means of tap bolts 14 extending completely 40 through the member 13 and threading into taps 15 in the upper face of the member 7. There is preferably provided a plurality of 45 these taps 15, thus permitting a step by step lateral adjustment of the roll 11 by successively securing the bolts 14 in different of the taps. This permits lateral adjustment of the roll 11 without changing the position of the other two rolls.

For the purpose of adjusting the two lower rolls 9 and 11 with respect to roll 10 50 but leaving the relative position of the rolls 9 and 11 unchanged, there is provided at each side of the apparatus a pair of adjusting screws 16 threaded through the upper ends of the pedestals 3 and abutting against the lateral faces of the supporting member 7. To permit lateral movement of the member 7 the retaining bolts 8 are fitted 55 through transverse slots 17 in the supporting member 6, the slots being of sufficient length to permit member 7 the maximum amount of lateral movement which may be required. A sprocket wheel 18 is provided at the outer 60 end of each of the adjusting screws 16; and the pair of screws at each side of the appa-

ratus are connected by a chain 19 working over the sprocket wheels 18 and serving to impart rotation to one of the screws whenever the other is rotated. In this manner binding of the member 7 against its retaining bolts is prevented since an equal pressure is exerted upon it at each end during the period of adjustment. The pair of adjusting screws at one side of the apparatus are used in adjusting the rolls rearwardly, 75 while the opposite pair serve to move the rolls in a forward direction.

For the purpose of effecting a vertical adjustment of the two lower rolls 9 and 11 the supporting member 6 rests upon the upper 80 ends of a pair of threaded posts 20, the lower ends of which are threaded for support in the worm wheel 27 which in turn is supported by the bed plate 1. A thrust collar 21 is provided at the upper end of 85 each of the posts 20, thus affording a satisfactory connection between the posts and the supporting plate 6 which prevents tilting of the supporting plate 6 on the posts 20. Rotation of the worm wheel 27 will cause 90 post 20 to be moved vertically up or down through a hole provided in the bed plate 1 and will consequently raise or lower the supporting plates 6 and 7 and the rolls 9 and 11 which are supported by them, a slot 95 being provided in each of the upstanding arms 22 of the member 6 through which the adjusting screws 16 extend to prevent these screws interfering with the vertical adjustment. For the purpose of preventing binding of the supporting member 6 on its track 100 during the operation of adjustment the posts 20 are arranged to be operated simultaneously. A shaft 23 is mounted a short distance above the bed plate and extends 105 longitudinally throughout the entire length of the machine having its bearing in a pair of brackets 24 extending upwardly from the bed plate 1 and in the upright pedestals 25 which are mounted upon the portion 2 of 110 the bed plate. At the portion of the shaft 23 adjacent the posts 20, worms 26 are provided to cooperate with worm wheels 27 which engage with the worms and also with the threaded posts 20. Rotation of the shaft 115 23 thus imparts rotation to the worm wheels 27 which in turn transmit vertical motion to the adjusting posts 20, a thrust bearing 28 being provided for taking up the end thrust on the worm wheel. During the operation 120 of vertical adjustment the shaft 23 is normally power driven, but for the purpose of effecting minute adjustments a hand wheel 29 is mounted in a bearing 30 carried by one of the supporting pedestals 3 and is connected to shaft 23 by means of a chain 31 working on sprocket wheels 32 provided on the shaft 23 and upon its own shaft. Rotation 125 of the hand wheel produces rotation of the shaft 23 from which motion is imparted to 130

the adjusting posts 20 by means of the worm and worm wheel, and a vertical adjustment of the rolls 9 and 11 is accomplished.

The upper roll 10 is carried by a shaft 33 whose inner end is mounted for rotation in the frame of the apparatus and whose outer end has a bearing in the upper end of an arm 34. This arm is pivoted at 35^a to the bed plate 1 and may be swung down horizontally to permit removal of a completed cylinder from the upper roll 10, the bearing at the upper end of the arm being tapered to correspond with the tapered end of shaft 33, which construction necessarily permits arm 34 to swing clear of shaft 33 without requiring a split bearing. The arm 34 when in its operative position fits into a pocket 36 formed in the stiffening member 37 which extends between the upper ends 20 of the pedestals 3, and a locking member 35 is provided to bridge over this gap and secure the pivoted arm in operative position, the locking member being held in place by means of bolts 38.

Power for driving the apparatus is supplied by an appropriate engine or motor through belts 39 and 40 operating over pulleys 41 and 42, respectively, the belt 39 serving to drive the mechanism in a forward direction and the belt 40 being crossed as shown to produce reverse rotation. The pulleys are rotatably supported upon a shaft 43 which is itself rotatably mounted in the upper ends of the pedestals 25 carried by the bed plate 2. Intermediate pulleys 41 and 42 is a sliding clutch 44 actuated by the clutch shifting lever 44^a, which may be moved to effect rotation of the shaft 43 in either the forward or reverse direction.

A pinion 45 is mounted at one end of shaft 43 and meshes with a gear 46 mounted on the outer end of a shaft 47, also having a bearing in the pedestals 25. At the outer end of shaft 47 there is mounted a second pinion 48 meshing with a large gear 49 which, by means of the shaft 50 and pinion 51, transmits motion to the driving gear 52 mounted directly on the shaft 33 of the driving roll 10. Power from the source may thus be transmitted through the gear reduction train to operate the roll 10 in either the forward or reverse direction, depending upon the position of the clutch shifting member 44. The shaft of the roll 9, best shown in Fig. 7, is also provided with a gear 53 which, through idlers 54 and 54^a, receives its motion from a second gear 55 mounted on the shaft 33 of the roll 10. The gears 53 and 55 are of the same size for effecting rotation of the rolls 9 and 10 at equal velocities and in reverse directions. For the purpose of providing for lateral and vertical adjustment of the roll 9 the idler 54 is mounted in a hanger 57 pivoted to the axis of the idler 54^a and provided with a

handle 58 to facilitate its adjustment. By this means the idler 54 may be swung around to mesh with gear 53 of the roll 9 in any position of adjustment and at the same time remain in mesh with idler 54^a. The hanger 70 is secured in position by means of bolts 59 set in the frame of the apparatus and working in a slot 60 for permitting the hanger a sufficient amount of rotative movement.

The main shaft 47 of the power transmitting mechanism also carries a centrally positioned pulley 61 connected by means of a belt 62 to a second pulley 63 rotatably mounted on the adjusting shaft 23. A sliding clutch 64 is provided in cooperation with the pulley 63 to effect rotation of the adjusting shaft as desired, the direction of rotation of the shaft being determined by the position of the clutch shifting lever 44.

The operating rolls 9 and 10 and 11 are substantially cylindrical in shape, each being provided with a corrugation similar to that contained in the sheet which is being rolled. Upper roll 10 is adapted to bear on the inner surface of the material and consequently has a raised corrugation 65, while the lower rolls 11 and 12 are provided with grooves adapted to receive within them the raised corrugation on the metal sheet A.

In the operation of the machine the rolls 9 and 10 are brought together in substantially tangential relation, sufficient space being left between them to admit the metal sheet. These rolls are brought into proper position by means of the vertical adjustment, the clutch 64 on the shaft 23 being moved into operative position for causing the vertical adjusting posts 20 to be raised or lowered and consequently move the rolls 9 and 11 in a vertical direction. When an approximate adjustment has been obtained the clutch 64 is disconnected and exact adjustment obtained by the manually operated hand wheel 29. Upon rotation of the rolls 9 and 10 the corrugated sheet of metal is passed between them and comes in contact with the surface of the roll 11, best shown in Figs. 8 and 9. If this point of contact lay in a line tangent to the cooperating rolls 9 and 10 at their point of contact with the metal no curvature would be imparted to the sheet. The apparatus is so designed, therefore, as to raise the roll 11 sufficiently so that its point of contact with the metal lies above a tangent line drawn to the rolls 9 and 10 at their cooperating faces and thus imparts a curvature to the metal sheet, the curvature being constant for any given position of the rolls.

It is evident that the diameter of the rolled cylinder will be less the greater the distance that the point of contact between the roll 11 and the metal is from a line drawn tangent to the rolls 9 and 10 at their cooperating faces. Consequently for cylin-

ders of large diameter the rolls 9 and 10 will be positioned so that the horizontal distance between their centers, indicated at 66, is small, since this is the position which more nearly brings the tangent line drawn to their cooperating surfaces to a horizontal direction. For forming cylinders of a smaller diameter the distance 66 will be increased, as shown in Fig. 8. This position of the rolls serves to incline the tangent line at a greater angle to the horizontal and consequently causes the roll 11 to impart a greater curvature to the metal sheet. This adjustment is obtained by first shifting the lower rolls laterally by means of the adjusting screws 16, and subsequently bringing them into proper vertical relation by the hand wheel 29. Further variation in the diameter of the cylinder may be obtained by shifting the block 13, which carries the roll 11 laterally by means of the tapped holes 15, upon the supporting member 7.

While I have described and illustrated a preferred embodiment of my invention it is to be understood that the details of construction may be varied within the full scope of the appended claims without departing from the spirit of the invention, which consists essentially in the provision of operating rolls and adjusting and driving means therefor by reason of which a cylinder of any size and thickness may be formed.

I claim:

35. 1. In an apparatus for forming expansion joints, means for forming the material of the joint into a substantially cylindrical shape, comprising a roll adapted to bear upon one side of the material, an adjustable support cooperating rolls carried by said adjustable support for bearing upon the opposite side of the material and imparting a curvature thereto, said rolls being shaped to present a cooperating circumferential ridge and groove to receive a corrugation formed in the material as presented to the rolls whereby the shaping rolls contact with the said corrugated material throughout its extent and thereby bend all portions thereof to the proper curvature, driving means for said rolls, and means operated by said driving means for adjusting said support in a vertical direction.
40. 2. In an apparatus for forming expansion joints, means for forming the material of the joint into a substantially cylindrical shape comprising a roll adapted to bear upon one side of the material, an adjustable support cooperating rolls carried by said adjustable support for bearing upon the opposite side of the material and imparting a curvature thereto, driving means for said rolls, means operated by said driving means for imparting an extensive vertical move-
45. ment to said support, and manually operated means for adjusting said support in a vertical direction.
50. 3. In an apparatus for forming expansion joints, means for forming the material of the joint into a substantially cylindrical shape comprising a roll adapted to bear upon the inner surface of the material, an adjustable support cooperating rolls carried by said support and bearing upon the opposite side of the material for imparting a curvature thereto, means for moving said rolls in a vertical direction, and independent means for relatively adjusting said rolls in a transverse direction comprising a second support carried by said above mentioned adjustable support and laterally adjustable on said first mentioned support.
55. 4. In an apparatus for forming expansion joints, means for forming the material of the joint into a substantially cylindrical shape comprising a roll adapted to bear on the inner surface of the material, a second roll arranged in substantially tangential relation to the first for acting against the outer surface of the material, driving means for said rolls comprising a power driven shaft and connections between said shaft and rolls, a third roll adapted to independently act against the outer surface of the material and impart a curvature thereto, a vertically adjustable support carrying said second and third rolls, whereby said two rolls are adjustable vertically as a unit, a second support carrying said third roll mounted on said vertically adjustable support and slidably laterally thereon for effecting relative lateral adjustment of said two rolls and means for securing said laterally movable support to said vertically adjustable support in various positions of adjustment.
60. 5. In an apparatus for forming expansion joints, means for forming the material of the joint into a substantially cylindrical shape comprising a roll adapted to bear upon the inner surface of the material and having formed thereon a circumferential ridge to enter a corrugation in the material as presented to the apparatus, a second roll arranged in substantially tangential relation to the first for acting against the outer surface of the material and having formed in it a circumferential groove to receive the corrugation in said material, a third roll adapted to independently act against the outer surface of the material and impart a curvature thereto, means for relatively adjusting said rolls to vary the degree of curvature, comprising a vertically adjustable support carrying said second and third rolls whereby said two rolls are adjustable vertically as a unit, a second support carrying said third roll mounted on said vertically adjustable support and slid-

able laterally thereon for effecting relative lateral adjustment of said two rolls and means for securing said laterally movable

support to said vertically adjustable support in various positions of adjustment, a power driven shaft, connections between said shaft and said tangentially arranged

rolls, and means for adjusting said connection for all positions of adjustment of said rolls.

In testimony whereof I affix my signature.

EDWARD A. DEWALD.
